FIG 2

FIG. 3.

INVENTOR.
RUSSELL R. WATERMAN
BY *A. B. Bourman*
ATTORNEY.

UNITED STATES PATENT OFFICE

RUSSELL R. WATERMAN, OF LONG BEACH, CALIFORNIA, ASSIGNOR TO FARMERS' NATIONAL BANK OF GREENVILLE, OHIO, TRUSTEE, OF GREENVILLE, OHIO, A CORPORATION OF OHIO

WATER SEAL FOR STEAM POWER PLANTS

Application filed April 22, 1926. Serial No. 103,810.

My invention relates to water seals for steam power plants, more particularly an apparatus for separating the air from the water being sent to the boiler pumps in a steam power plant, and the objects of my invention are: first, to provide a means for separating the air from the water in its passage from the condenser to the boiler and releasing it to atmosphere; second, to provide a device of this class which is positive in its action; third, to provide an apparatus of this class which will operate efficiently using either atmospheric pressure or partial vacuum on the condenser; fourth, to provide a 10 novelly constructed water seal of this class; and, fifth, to provide an apparatus of this class which is very simple and economical of construction, positive in its action, efficient, durable and which will not readily deteriorate or get out of order.

With these and other objects in view as will appear hereinafter, my invention consists of certain novel features of construction, combination and arrangement of parts and portions as will hereinafter be described in detail and particularly set forth in the appended claims, reference being had to the accompanying drawings and to the characters of reference thereon which form a part of this application, in which:

Figure 1 is a diagrammatic, sectional view of my apparatus through 1-1 of Fig. 2, showing some of the parts and portions in elevation to facilitate the illustration; Fig. 25 2 is a sectional view through 2-2 of Fig. 1, and Fig. 3 is a fragmentary, sectional view through 3-3 of Fig. 1.

Similar characters of reference refer to similar parts and portions throughout the 40 several views of the drawings.

The separating chamber 1, separating chamber cover 2, diaphragm 3, water valve stem 4, float 5, float supporting arm 6, air valve 7, float arm pivot bolt 8, air outlet conductor 9, water valve stem spring 10, drain valve 11, water valve 12, water outlet conductor 13, conductor 14, bypass piston valve 15, branch conductor 16, bypass valve intake passage 17, condenser pump intake 18, gear pump 19, pump drive shaft 20, and stuffing

box 21 constitute the principal parts and portions of my water seal apparatus.

The separating chamber housing 1 is a hollow, cylindrical member provided with a flange 1a at its upper end over which is mounted a cover member 2 which is also provided with a flange 2a conforming to the flange 1a, and interposed between the flanges 1a and 2a, extending across the upper end of the member 1, is a diaphragm 3. Secured to this diaphragm 3 is the upper end of the valve stem 4, which valve stem 4 is provided on its upper end above said diaphragm with a flanged washer 4a upon which is mounted the compression spring 10 which is positioned in an inverted cup shaped portion 2b mounted centrally on the cover member 2. Thus it will be noted that there is provided both the spring 10 and the diaphragm 3 for regulating the movement of the valve stem 4. Secured on the lower end of the valve stem 4 is a valve 12 which seats in an orifice 1b in the lower central portion of the housing 1. This housing 1 is provided below the orifice 1b with a side outlet 13 which connects the chamber 1 with the boiler pump intake. It is also provided with a valve 11, which serves as a drain valve for draining both the chamber 1 and the conductor 13. Mounted around the valve stem 4 is a float member 5 which is pivotally supported on the arm member 6 which is pivoted on the bolt 8 and provided with a slot 6a in which is a pin mounted in the valve 7 which is the air outlet valve which seats in the opening to the conductor 9 as shown best in Fig. 1 of the drawings, it being noted that the lower end of this valve member 7 rests in a recess in a casing 1, it also being noted that the housing 1 is provided with an offset portion to accommodate the 85 valve 7 and the extended end of the lever 6 as shown best in Fig. 1 of the drawings. This lever 6, it will be noted, is furcated at its opposite ends so that it is positioned on opposite sides of lugs on the float 5 and also on the opposite sides of the valve 7. The conductor 14 which communicates with the lower side of the housing 1, communicates with one side of a gear pump 19 which is of the conventional type, and the other side communi-

cates with the conductor 18 which leads to the condenser. This conductor 18 is provided with a branch 16 which communicates with a small orifice 15a in the piston 15 which is 5 reciprocally mounted in an upright housing 15d in which the piston is mounted, and this piston is provided with a spring 15c, tending to hold it downwardly against shoulders 15b in the housing 15d. The interior of 10 this housing is provided with a bypass 17 communicating with the conductor 14. The pump 19 is provided with an extended shaft 20 provided with a housing upon which is mounted a stuffing box 21 for providing a seal 15 around the said shaft.

The operation of the water seal apparatus is as follows: water is pumped from the condenser by means of the gear pump 19 and passes through the conductor 14 into the 20 chamber 1 in which the air separates from the water and raises to the upper portion of the chamber and the water settles to the lower portion. When the water reaches a certain level in the housing 1, the float 5 is raised, 25 closing the outlet valve 7, thus building up a pressure in chamber 1 and raising the diaphragm 3 which in turn raises the valve 12 off from seat 1b and allows the water to pass to the conductor 13, thence to the boiler 30 pump, not shown. If however the supply of water in the housing 1 is low, the float 5 will lower, which in turn will lower the valve 7 and permit air to pass through the outlet 9 to atmosphere or to the condenser. In case 35 the pressure is high in the housing 1, the pressure of the water caused by the pump 19 will raise the piston 15 and permit the water and air to bypass through the conductor 16 back to the conductor 18 and through the 40 pump again. When the pressure lowers in the chamber 1, the valve 12 will close on the seat 1b, thus not allowing the water level in chamber 1 to drop low enough to allow air to pass through the valve 12 into the conductor 13 and into the boiler pump. When 45 more water is supplied it will then pass directly from the condenser and into the pump 19 into the housing 1, raising the pressure, whereupon the diaphragm 3 will cause the 50 valve 12 to be raised and permit the boiler pump to draw water from the housing 1.

Though I have shown and described a particular construction, combination and arrangement of parts and portions, I do not 55 wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In a water seal apparatus for steam 65 power plants, a separating chamber connect-

ed to a water supply and provided with a diaphragm in its upper end, a valve supported by said diaphragm and seated in the lower end of said chamber, a float actuated valve communicating with said chamber near the 70 upper side thereof, an outlet conductor communicating with said chamber through said valve at the lower end of said chamber, and a second discharge conductor connected to the upper portion of said chamber and controlled by said float actuated valve. 75

2. In a water seal apparatus, a separating chamber member having a side wall and a discharge opening at its lower end, an inlet opening at its lower portion, and a second discharge opening at its upper portion, a diaphragm at the upper end of the chamber member, a valve mounted over the discharge opening at the lower end, a stem connecting the diaphragm to the valve, a second valve 80 in the side wall of the chamber member for controlling the second discharge opening, a float mounted within the chamber member around the stem, and a lever pivotally mounted within the chamber member operatively 85 connected to the second valve, said lever extending inwardly from its side wall and pivotally connected at its inner end to the float. 90

3. In a water seal apparatus, a separating chamber member having a discharge opening 95 at its lower portion, an inlet opening at said lower portion, and a second discharge opening at its upper portion, a diaphragm at the upper end of the chamber member above the second discharge opening, a valve mounted over the discharge opening at the lower portion of the chamber member and operatively connected to said diaphragm, and a float controlled valve for controlling the discharge 100 of fluid through the second discharge opening. 105

In testimony whereof, I have hereunto set my hand at Los Angeles, California, this 15th day of April, 1926.

RUSSELL R. WATERMAN.
